Specification for Design.

Patented Aug. 29, 1911.

Application filed May 6, 1911. Serial No. 625,653. Term of patent 3½ years.

To all whom it may concern:

Be it known that I, GUSTAVE M. FAUSER, a citizen of the United States of America, residing at the borough of Manhattan, in the city of New York, in the county and State of New York, have invented a new, original, and ornamental Design for Textile Fabrics, of which the following is a specification, reference being had to the accompanying drawing, forming a part thereof.

The figure is a plan view of a portion of the fabric, showing my new design.

In the drawing A, A, represent large shield shaped leaves, and B, B, are flowers similar to those of lotus.

C, C, are flower buds.

I claim:

The ornamental design for a textile fabric, as shown.

GUSTAVE M. FAUSER.
